(57) **ABSTRACT**

A hair styler includes detachable heating bars which allows a user to easily change a set of existing heating bars with another set of such bars and easily fasten the newly attached heating bars to the arms of the styler without separate fasteners. Two heating bars are provided, each including an insulator assembled through a slide type engagement. The insulators have both a hook and a locking flange at each end thereof. One arm detachably seats the first heating bar therein, and includes an electrical circuit, a power switch, and a temperature controller, along with a locking recess for removably receiving the hook of one of the insulators. A second arm seats the second heating bar therein, and a jointing unit connects the first and second arms to form a tongs shape. Power is supplied to the styler by an electric cord.

1 Claim, 5 Drawing Sheets

FIG.1
PRIOR ART

FIG.2

FIG.3

FIG.4a

FIG.4b

HAIR STYLER WITH DETACHABLE HEATING BARS

BACKGROUND OF THE INVENTION

1. Field of the Invention

The present invention relates, in general, to hair stylers with detachable heating bars and, more particularly, to a hair styler designed to allow a user to easily change a set of existing heating bars with another set of bars and easily fasten the newly attached heating bars to the arms of the styler without using a separate fastening means.

2. Description of the Prior Art

In a conventional hair styler that is an electric appliance for setting or styling the hair, two detachable heating bars 2 are screwed to the two arms 1 of the styler using a plurality of setscrews tightened into the screw holes 3 formed at the two arms 1, as shown in FIG. 1. An electric circuit is set in one of the two arms 1 for heating the two heating bars 2 using electric power supplied from an external power source through a cord 4. The two arms 1 are hinged to each other at their ends by a joint 5 to form a tongs shape.

Such a hair styler typically has several sets of heating bars, which have different shapes at their styling surfaces for allowing a user to create different hair styles as desired. When it is desired to create a new hair style, the user changes a set of existing heating bars with another set of bars prior to styling his or her hair.

However, when it is desired to change a set of existing heating bars with another set of bars, the conventional hair styler forces a user to loosen the setscrews from the two arms of the styler, remove the existing bars from the arms, seat the new bars in the empty arms, and fasten the new bars to the arms by tightening the setscrews. Such conventional hair stylers are thus inconvenient to users.

In addition, the heating bars are directly attached to the arms of the conventional hair stylers without using any insulator interposed between the arms and the bars, and so the heating bars undesirably heat the arms during a hair styling work. Users of the stylers are thus forced to be careful of the hot arms while setting or styling the hair.

SUMMARY OF THE INVENTION

Accordingly, the present invention has been made keeping in mind the above problems occurring in the prior art, and an object of the present invention is to provide a hair styler, which has several sets of detachable heating bars and is designed to allow a user to easily change a set of existing heating bars with another set of bars and easily fasten the newly attached heating bars to the arms without using a separate fastening means.

Another object of the present invention is to provide a hair styler, which has insulators interposed between the arms and the heating bars, thus reducing danger of burning to users caused by excessively heated arms while setting or styling the hair.

In order to accomplish the above objects, the present invention provides a hair styler, comprising: two heating bars each assembled with an insulator through a slide type engagement, the insulator having both a hook and a locking

flange at each end thereof; a first arm detachably seating a first one of the two heating bars therein, the first arm including: an electric circuit applying electric power from an external power source to the two heating bars; a power switch for turning on or off the electric circuit; a temperature controller for controlling a temperature of heat dissipated from the two heating bars; a first locking recess for removably receiving the hook of the first heating bar therein; a support protrusion for thermally insulating the first arm from the first heating bar and supporting the first heating bar in the first arm; and a cover for covering the electric circuit to conceal the circuit from the outside of the hair styler; a second arm having a second locking recess for removably receiving the hook of the second heating bar in the second locking recess; a jointing unit provided at ends of the first and second arms for jointing the arms together to form a tongs shape; and an electric cord connected to the hair styler for applying electric power from the external power source to the electric circuit.

BRIEF DESCRIPTION OF THE DRAWINGS

The above and other objects, features and other advantages of the present invention will be more clearly understood from the following detailed description taken in conjunction with the accompanying drawings, in which:

FIG. 1 is a perspective view of a conventional hair styler;

FIG. 2 is a perspective view of a hair styler in accordance with the preferred embodiment of the present invention;

FIG. 3 is an exploded perspective view of the hair styler of FIG. 2;

FIG. 4a is a sectional view of a heating bar included in the hair styler of this invention; and

FIG. 4b is a perspective view, showing the structure for assembling an insulator with the heating bar of this invention.

DETAILED DESCRIPTION OF THE INVENTION

Reference should now be made to the drawings, in which the same reference numerals are used throughout the different drawings to designate the same or similar components.

FIGS. 2 and 3 are views of a hair styler in accordance with the preferred embodiment of this invention. As shown in the drawings, the hair styler of this invention has two jointed arms, that is, first and second arms 10 and 20. First and second heating bars 30 are easily, simply and detachably attached to the two arms 10 and 20, and dissipate heat to the hair during hair styling when the two bars 30 are electrically activated by electric power applied from an external power source through an electric circuit (not shown) which is set in the first arm 10. Each heating bar 30 also has an insulator 31, which insulates the heating bar 30 to prevent heat transfer from the bar 30 to an associated arm 10 or 20. The heating bar 30 has a hook 31a and two locking flanges 31b at each end of the insulator 31 such that the heating bar 30 is easily, simply and detachably assembled with an associated arm 10 or 20.

The first arm 10, which is detachably seated in one heating bar 30, has a plurality of first support protrusions 12 and a first locking recess 13. The support protrusions 12

support the heating bar **30** in the first arm **10** to prevent an undesired movement of the bar **30** in the first arm **10**. The support protrusions **12** also have a thermal insulating function in that they separate the heating bar **30** from the arm **10**, and reduce thermal damage to the arm **10** caused by the heating bar **30**. The first locking recess **13** removably receives the hook **31a** of the heating bar **30** therein such that the heating bar **30** is closely and detachably seated in the first arm **10**. The first arm **10** also has a control unit, which is screwed to the arm **10** and fabricated with two covers **11** and **14**. The control unit has the electric circuit (not shown), which controllably applies electric power from an external power source to the two heating bars **30** of the first and second arms **10** and **20**, thus allowing the two heating bars **30** to dissipate heat to the hair during a hair styling work. The control unit also has a power switch **14a**, by which a user turns on or off the hair styler. The control unit further includes a temperature controller **14b**, by which the user controls the temperature of heat dissipated from the two heating bars **30**. The two covers **11** and **14** of the control unit cover the electric circuit to conceal the circuit from the outside of the hair styler.

The second arm **20** is jointed to the first arm **10** at their ends to form a desired tongs shape, and has a plurality of second support protrusions **12** and a second locking recess **13** which have the same functions as those of the first arm **10**.

In order to joint the two arms **10** and **20** to each other at their ends to form a desired tongs shape, a jointing unit **40** is provided at the ends of the two arms **10** and **20**.

An electric cord **50**, having a plug, is connected to the hair styler, and applies electric power from the external power source to the control unit.

The two arms **10** and **20** are jointed to each other at the jointing unit **40**, thus forming a desired hair styler having a tongs shape, in which the two heating bars **30** of the two arms **10** and **20** thermally set or style the hair while gripping the hair when the two arms **10** and **20** are closed by a user.

In the present invention, it is preferred to joint the two arms **10** and **20** at the jointing unit **40** using a hinging means.

FIGS. **4a** and **4b** are view, showing the structure for assembling the insulator with the heating bar of this invention. In order to detachably assemble the insulator **31** with the heating bar **30** of this invention, a locking groove **30a** is formed along each longitudinal edge of the heating bar **30**. A locking rail **31c** is formed along each longitudinal edge of the insulator **31**, and removably engages with the locking groove **30a** of the heating bar **30**.

In such a case, the engagement of the bar **30** with the insulator **31** is preferably accomplished by a slidable engagement. A supporter **30b** is set on the inner surface of the heating bar **30**. This supporter **30b** prevents the insulator **31** from excessively passing over the heating bar **30** when assembling the insulator **31** with the heating bar **30**, and supports the insulator **31** on the heating bar **30**.

Due to the two locking flanges **31b** formed at each end of the insulator **31**, the insulator **31** is less likely to be undesirably removed from the heating bar **30**.

As shown in FIGS. **2** and **3**, the lower cover **11** of the control unit has a plurality of screw holes **11a**, at which the

control unit is fastened to the first arm **10** using a plurality of setscrews. A plurality of internally-threaded bosses are formed at the first arm **10** for fastening the control unit to the first arm **10** using the setscrews. In addition, a circuit holder (not shown) is provided in the first arm **10** for holding the electric circuit in the arm **10**.

The electric circuit is set in the first arm **10**, and controllably applies electric power to the two heating bars **30** of the first and second arms **10** and **20**. Such an electric circuit is not set in the second arm **20**, but is only set in the first arm **10**.

The operational effect of the hair styler having such detachable heating bars of this invention will be described herein below.

In order to assemble the insulator **31** with the heating bar **30**, the insulator **31** slides on the heating bar **30** from an end of the bar **30** after initially engaging the two locking rails **31c** of the insulator **31** with the two locking grooves **30a** of the heating bar **30**. When the insulator **31** is completely assembled with the heating bar **30**, the insulator **31** is less likely to be undesirably removed from the heating bar **30** due to both the locking flanges **31b** of the insulator **31** and the supporter **30b** of the heating bar **30**.

After two heating bars **30** are assembled with two insulators **31**, respectively, the two heating bars **30** are respectively attached to the two arms **10** and **20** by engaging the hooks **31a** of the insulators **31** of the heating bars **30** with the locking recesses **13** of the arms **10** and **20**. In such a case, the insulator **31** of each heating bar **30** comes into close contact with the support protrusions **12** of an associated arm **10** or **20**, and so the heating bar **30** is stably held in the arm so as to be prevented from an undesired movement within the arm.

In order to use the hair styler, a user connects the cord **50** to an external power source prior to turning on the power switch **14a** of the control unit set in the first arm **10**.

Thereafter, the user sets a desired temperature of heat dissipated from the heating bars **30** by manipulating the temperature controller **14b**. The circuit thus transmits electric power to the two heating bars **30** of the two arms **10** and **20** such that the two bars **30** dissipate heat of the adjusted temperature.

The user positions the two arms **10** and **20** of the hair styler around the hair, and closes the arms **10** and **20** by compressing them such that the two arms rotate around the jointing unit **40**, with the two heating bars **30** of the arms **10** and **20** gripping the hair. The two heating bars **30** thus thermally set or style the hair to create a desired hair style.

As described above, the present invention provides a hair styler with detachable heating bars. This hair styler is designed to allow a user to easily change a set of existing heating bars with another set of bars and easily fasten the newly attached heating bars to the arms of the styler without using a separate fastening means. This hair styler is thus convenient to users.

In this hair styler, an insulator is assembled with each heating bar such that the insulator is interposed between the heating bar and an associated arm, thus reducing danger of burning to users caused by excessively heated arms while setting or styling the hair.

Although a preferred embodiment of the present invention has been described for illustrative purposes, those skilled in the art will appreciate that various modifications, additions and substitutions are possible, without departing from the scope and spirit of the invention as disclosed in the accompanying claims.

What is claimed is:

1. A hair styler, comprising:

two heating bars each assembled with an insulator 10 through a slide type engagement, said insulator having both a hook and a locking flange at each end thereof; a first arm detachably seating a first one of the two heating bars therein, said first arm including:
an electric circuit applying electric power from an 15 external power source to the two heating bars;
a power switch for turning on or off the electric circuit;
a temperature controller for controlling a temperature of heat dissipated from the two heating bars;

a first locking recess for removably receiving the hook of the first heating bar therein;
a support protrusion for thermally insulating the first arm from the first heating bar and supporting the first heating bar in the first arm; and
a cover for covering the electric circuit to conceal the circuit from the outside of said hair styler;

a second arm having a second locking recess for removably receiving the hook of the second heating bar in the second locking recess;

a jointing unit provided at ends of the first and second arms for jointing said arms together to form a tongs shape; and

an electric cord connected to the hair styler for applying electric power from the external power source to the electric circuit.
